CAP

Filed March 21, 1925

UNITED STATES PATENT OFFICE.

BENJAMIN BENNO, OF DALLAS, TEXAS.

CAP.

Application filed March 21, 1925. Serial No. 17,361.

This invention relates to new and useful improvements in caps.

The object of the invention is to provide a hair protecting cap made of washable material and so constructed that it may be ironed flat.

A further object of the invention is to provide a cap having means for shaping it in an attractive and convenient form.

Another object is to provide means for fastening down the corners of the cap to shape it for wearing.

A further object is to provide a cap which may be formed from a single piece of material folded upon itself if desired.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a plan view of the cap laid out for ironing,

Fig. 2 is an elevation of the cap with its corners folded down and fastened,

Fig. 3 is an enlarged vertical sectional view on the line 3—3 of Fig. 1,

Fig. 4 is an enlarged cross-sectional view on the line 4—4 of Fig. 1, and

Fig. 5 is a side view of the cap when ready to wear.

In the drawings the numeral 10 designates a piece of cloth or other suitable material of a rectangular or other suitable shape folded upon itself along the line 11. The sides of the material are overlapped and seamed together at 12. In order to shape the cap the sides of the material may be overlapped more at the bottom than at the top, thus making the cap slightly smaller at the bottom than at the top, but this is not essential. The lower end of the back panel 13 of the cap may be formed with a casing 14 to receive a draw string 15.

On the front panel 16 a head band 17 may be sewed as a reinforcement or for ornamental purposes. This band has its ends secured in the side seams 12. Also tucks 18 may be stitched in the back panel 13 to arch the lower edge thereof so that it will better fit the neck of the wearer. The draw strings

15 pass out through an eye 19 at the center of the casing.

At each side of the cap the overlapped seams 12 are each provided with a pair of spaced eyelets or buttonholes 20, which are located at the desired distance from the upper corners of the cap. To each corner is 60 suitably sewed a pair of short tapes or strings 21. To shape the cap its corners are folded down on each side as is shown in Figs. 2 and 5 and the strings 21 are threaded through the eyelets 20 and tied inside the cap. When the cap is placed on the head of the wearer the draw strings 15 are drawn together and tied, whereby the back edge is gathered and the cap is fastened in place.

When it is desired to wash the cap the strings 15 are untied and the strings 21 are also untied so that the folded corners of the cap may be straightened out. After the cap has been washed it may be ironed flat and 75 can be handled through a mangle in a laundry as "flat" work. The cap is easy to iron and may be starched if desired. While I have shown eyelets and strings for fastening down the corners, it is apparent 80 that other means could be used.

Various changes in the size and shape of the different parts, as well as modifications and alterations may be made within the scope of the appended claims.

What I claim, is:

1. A cap of the character described comprising parallel front and rear panels united to lie in contact with each other when not in use and forming a crown of substantially angular outline with foldable corners at the sides thereof, and means for fastening said corners when folded downward upon the body of the cap when in use.

2. A cap of the character described comprising parallel front and rear panels formed with corners at opposite sides of the crown and having openings at its side edges, and strings fastened to the upper corners of the crown for passing through said openings and being tied within the cap when the corners thereof are folded downwardly.

In testimony whereof I affix my signature.

BENJAMIN BENNO.
